UNITED STATES PATENT OFFICE.

DELBERT A. SECOR, OF CASSOPOLIS, MICHIGAN, ASSIGNOR OF ONE-HALF TO JOHN SCHMIDT, OF DOWAGIAC, MICHIGAN.

CYLINDRICAL WALL STRUCTURE SUCH AS A SILO.

1,195,277.

Specification of Letters Patent. Patented Aug. 22, 1916.

Application filed October 18, 1915. Serial No. 56,530.

To all whom it may concern:

Be it known that I, DELBERT A. SECOR, a citizen of the United States, residing at Cassopolis, county of Cass, State of Michigan, have invented certain new and useful Improvements in Cylindrical Wall Structures, such as Silos, of which the following is a specification.

This invention relates to improvements in 10 cylindrical wall structures, such as silos.

The main objects of my invention are: First, to provide an improved cylindrical wall structure adapted for silos and similar structures in which the blocks are effectively 15 interlocked and are all effectively engaged by the encircling hoops. Second, to provide an improved cylindrical wall structure having a series of door openings, one above the other, separated only by relatively narrow 20 horizontal members in which the parts, even at the door openings, are thoroughly interlocked and supported.

Further objects, and objects relating to 25 structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a front elevation of a silo embodying the features of my invention. Fig. II is a detail inside elevation showing the arrangement of the door casing and jamb blocks in the wall. Fig. III is an enlarged detail horizontal section on a line corresponding to line 3—3 of Fig. I. Fig. IV is a detail vertical section on a line corresponding to line 4—4 of Fig. I, showing the arrangement of the doors in their frames or casings. Fig. V is a detail vertical section on a line corresponding to line 5—5 of Fig. I, showing the interlocking ribs and grooves of the blocks or staves. Fig. VI is a front perspective view of one of the casing blocks. Fig. VII is a front perspective view of one of a pair of jamb blocks. Fig. VIII is a front perspective view of the other of a pair of jamb blocks. Fig. IX is

a detail end view of the jamb block shown in Fig. VIII. Fig. X is a detail end view 55 of the jamb block shown in Fig. VII.

In the drawing similar reference characters refer to similar parts throughout the several views, and the sectional views are taken looking in the direction of the little 60 arrows at the ends of the section lines.

Referring to the drawings, 1 represents a concrete foundation for a silo. The blocks or staves are preferably formed of concrete or artificial stone. The wall is preferably 65 begun and finished with half blocks or staves 2. I use the term blocks herein although the blocks are relatively long in proportion to their width and are commonly designated as staves by the trade. 70

The wall blocks 3 are provided with central recesses 4 in their ends forming pairs of interlocking end projections 5 at each end. The sides 6 of these recesses diverge outwardly. The blocks are preferably 75 curved in cross section. One edge of each block is provided with a rib or tongue 7, while the other is provided with a corresponding groove 8, so that when the blocks are laid in the walls these ribs and grooves 80 engage, as is shown in Fig. III. One end of each block is provided with a tongue or rib 9 while the other is provided with a complementary groove 10 adapted to coact with the tongues and grooves of the blocks 85 of adjacent courses.

The blocks 3 are laid in courses with their meeting interlock projections fitting recesses of the blocks of adjacent courses and interlocking with the interlock projections thereof, so that the interlock projections of each course are interlocked with the interlock projections of the course above and below, each block constituting a tie member for the four blocks with which its 90 ends abut. The tongues or ribs of one block fit the grooves of the abutting block, so that the wall blocks are interlocked throughout their length as well as at their ends, the end 95 grooves and tongues being interlocked as well as the end interlock projections. The grooves and ribs, in addition to their value in supporting the blocks in alignment, are of value in forming an air-tight wall, which is required in satisfactory silo construction. 100 105

A series of doors, one above the other, are

provided by laying casing blocks 11 in alternate courses of the wall blocks. These casing blocks are provided with ribs 12 on one edge coacting with the grooves of the adjacent wall blocks of the courses and with grooves 13 on the opposite edge coacting with the rib of the adjacent block of the course. Jamb blocks 14 and 15 are laid in the courses alternately with the casing blocks. These jamb blocks are very similar in shape to the regular wall blocks, being provided with end recesses 4 forming interlock projections 5 and 5'. The interlock projections 5 at the inner edges of the jamb blocks are interlocked with the interlock projections of the wall blocks abutting their ends. The interlock projections 5' are somewhat shorter than the interlock projections 5 and coact with complementary recesses and projections 16 and 17 at the edges of the casing blocks 11. This brings the horizontal members 18 of the casing blocks 11 into alignment with the interlock projections of the wall blocks and also brings the horizontal members 18 into position, so that they lap the ends of the jamb blocks and constitute cross members for the wall course in which the jamb blocks are laid as well as cross members for the wall course in which the casing blocks are laid. The casing blocks and the jamb blocks are so disposed that the door openings of the casing blocks 19 and the door openings 20 between the casing blocks are of the same size so that the doors 21 may be interchanged. The meeting parts of the casing and jamb blocks are provided with coacting ribs 22 and 23. The shoulder portions 24 of the casing blocks, which engage the inner edges of the jamb blocks, are provided with ribs 25 and grooves 26 coacting with corresponding ribs and grooves 27 and 28, respectively, on the jamb blocks 14 and 15.

The edges of the door openings 19 are rabbeted at 29 to receive the doors 21. The jamb blocks are rabbeted at 30 to provide door receiving recesses while the upper edge of the top cross member and the lower edge of the bottom cross member of the casing blocks are rabbeted at 31, thus providing continuous rabbets or recesses for the alternate doors. The doors are retained by bars 32 engaged behind suitable keepers 33. This detail of securing the doors forms no part of my present invention.

The encircling hoops 34 are disposed across the interlocked end projections of the blocks and the door and jamb blocks and across the horizontal members or top and bottom members of the casing blocks, and the hoops are disposed so that all the blocks are effectively engaged by the hoops. By this arrangement the blocks are interlocked at the door opening as well as in the wall structure proper, thus providing a wall that

cannot collapse and is self-sustaining, even without hoops, as the parts are so thoroughly and completely interlocked.

The structure illustrated is provided with a conical roof 35 which, however, forms no part of my present invention.

I have illustrated and described my improved wall structure as I have embodied the same in silos for which it is particularly adapted. The blocks or staves are, as stated, interlocked throughout so that it is quite impossible for them to become displaced on account of wind strains or settling or ordinary racking strains. A further advantage is that the joints between the blocks are substantially air-tight, which is a feature of great advantage in silo structures.

Having thus described my invention, what I claim as new and desire to secure by Letters Patent, is:

1. A cylindrical wall structure of the class described comprising wall blocks having spaced interlock projections at each end, said blocks being laid in courses to break end joints with the blocks of adjacent courses and with their interlock projections interlocked with an interlock projection of each block of the adjacent courses with which they abut, casing blocks laid in alternate courses of said wall blocks and having door openings therein, said casing blocks having end interlock projections adjacent their side edges, jamb blocks laid in said wall courses alternately with said casing blocks and having spaced interlock projections at each end interlocked with interlock projections of said casing blocks and wall blocks abutting said casing blocks, the horizontal members of said casing blocks constituting cross members between the ends of said jamb blocks, and encircling hoops disposed across the said interlock projections of said blocks and across the horizontal pieces of said casing blocks.

2. A wall structure of the class described comprising wall blocks having spaced interlock projections at each end, said blocks being laid in courses to break end joints with the blocks of adjacent courses and with their interlock projections interlocked with an interlock projection of each block of the adjacent courses with which they abut, casing blocks laid in alternate courses of said wall blocks and having door openings therein, said casing blocks having end interlock projections adjacent their side edges, jamb blocks laid in said wall courses alternately with said casing blocks and having spaced interlock projections at each end interlocked with interlock projections of said casing blocks and end wall blocks abutting said casing blocks, the horizontal members of said casing blocks constituting cross members between the ends of said jamb blocks.

3. A cylindrical wall structure of the class

described comprising a series of courses of blocks having interlocking ends and sides in combination with frame-like door casing blocks laid in alternating courses in said wall, said casing blocks having door openings therein, the spaces between the casing blocks also constituting door openings, the ends of said casing blocks being shouldered to abut with the ends of blocks of the adjacent courses, and encircling hoops disposed across the interlocking ends of said courses of said blocks and the ends of said casing blocks.

4. A cylindrical wall structure of the class described comprising a series of courses of blocks having interlocking ends in combination with frame-like door casing blocks laid

in alternating courses in said wall, said casing blocks having door openings therein, the spaces between the casing blocks also constituting door openings, the ends of said casing blocks being shouldered to abut with the ends of blocks of the adjacent courses, and encircling hoops disposed across the interlocking ends of said courses of said blocks and the ends of said casing blocks.

In witness whereof, I have hereunto set my hand and seal in the presence of two witnesses.

DELBERT A. SECOR. [L.S.]
